LAST OPERATING DEVICES

Henry F. Loewer, Rochester, N. Y., assignor to United Shoe Machinery Corporation, Flemington, N. J., a corporation of New Jersey

Application November 6, 1953, Serial No. 390,577

1 Claim. (Cl. 12—15)

This invention relates to mechanisms for opening and closing collapsible shoe lasts of the type disclosed in United States Letters Patent No. 2,404,805, granted July 30, 1946, on application of V. J. Levaggi, Jr.

This type of last is provided with a strong but resilient tension spring which acts as a link to lock the heel and the forepart of the last together in closed relation. This link is in the form of a single piece of heavy spring wire having two flexible arms and an arcuate return bend connecting them and adapted to extend around and engage a pivot pin in the forepart of the last; the free end of one of said arms having a bend adapted to extend around and engage a pivot pin in the heel part; while the other of said arms has an intermediate bend forming a latching shoulder adapted to cooperate with a latching pin in the heel part to thereby lock the last in closed position. A free end portion of this latch arm extends beyond the latching shoulder to a position adjacent the last spindle socket. The link may be unlocked, in order to collapse the last, by engaging the resilient free end portion and forcibly deflecting it in such a direction as to increase the spread between the arms until the latching pin is freed from the latching shoulder. The deflection of the latching arm may conveniently be effected by movably engaging its free end with a finger-like implement inserted into the last through an opening in the adjacent last spindle socket.

The purpose of this invention is to provide an inexpensive and effective manually operated device for unlocking a collapsible last in the above-described manner.

One of the novel features of this last operating device is the provision of a movable last mounting spindle initially supported in an inclined position for receiving a last when presented to the device with the last inverted and its toe end inclined downward. This movable spindle has a mortise recess therein which accommodates a last unlatching finger when the spindle is in its initial inclined position.

A further feature of the invention is that the spindle, after a last to be opened has been placed thereon, may be pivotally moved in a vertical plane by merely pulling upward on the toe end of the last, and this movement of the spindle causes the unlatching finger to be exposed and left projecting outward from the interior of the spindle where it may be engaged by the free end of the latching arm of the last link and, upon further movement of the spindle toward its upright or vertical position, the relative movement between the finger and the last frees the latching shoulder on the last link arm from the latching pin thereby unlocking the last which has, during the unlocking operation, been elevated to a substantially horizontal position in which position a shoe may be most conveniently mounted upon or removed from the collapsed last.

Another advantageous feature of the invention is the provision of a releasable stop mechanism on the last operating device for firmly holding the unlocked last in

2

the horizontal position while the shoe mounting or removing operation is being performed.

Still another feature of the invention is the novel mechanism which causes the last supporting spindle to enclose or expose the unlatching finger in response to the pivotal shifting movement of the spindle.

One of the advantages of this last operating device is its compact construction which readily permits the device to be screwed or bolted, at a chosen height above the floor, to any convenient work supporting structure such as a work bench or the frame portion of a shoe manufacturing machine.

The above and other objects and features of this invention will appear from the following detailed description of the preferred embodiment thereof illustrated in the accompanying drawings, and will be pointed out in the claim.

In the drawings,

Fig. 1 is a side elevation view of the device, with a locked last positioned thereon in its initial or inclined position;

Fig. 2 is a similar view showing portions broken away and in section and showing the device in its upright position with the last unlocked and collapsed;

Fig. 3 is an exploded view of parts of the device shown partially broken away and in section;

Fig. 4 is a top plan view of the device in its upright position;

Fig. 5 is a front elevation view of the device in upright position; and

Fig. 6 is an enlarged fragmentary cross sectional view showing a detail as viewed along the line VI—VI of Fig. 1 and looking in the direction of the arrows.

Referring to these drawings and particularly to Figs. 1, 2 and 3, the last operating device therein illustrated consists of a stationary upright frame plate 12 providing a pedestal upon which the last operating mechanism is supported. This pedestal is secured to a suitable mounting member, such as a table top T, by bolts or screws passing through a horizontal flange portion 14. The movable head portion of the operating mechanism, designated generally by the arrow 1, is fabricated in laminate form, as will be described hereinafter, and is movably mounted upon the upper portion of the plate 12 by means of a pin 16 extending through a transverse hole 18 in the plate 12 (Fig. 3). A vertical side portion of the plate is relieved so as to form a socket 20, adjacent the hole 18, into which socket fits the base of an unlatching finger 22. This base is attached within the socket by the pin 16 which passes through a hole 24 in the base, and the finger when so attached is secured against pivotal movement about said pin by reason of the fact that the base of the finger has a non-circular edge portion 26 contiguous to a wall portion 28 of the socket. The last unlatching finger is thus rigidly held above the stationary upright frame plate 12.

Referring now to Figs. 3, 4 and 5, it will be seen that, as above mentioned, the movable head portion of the operating mechanism comprises a series of plates, secured together in parallel relationship by screw fastenings passing transversely through the plates, with a last supporting spindle rigidly attached thereto by one of said screws. The two outside plates 30, 31, which will be referred to as the housing members of the movable head portion 1, have nested therebetween a set of spindle-holding guide plates 32, 33. These plates 32, 33 are provided respectively with an arcuate guide slot 34, 35, so that when assembled, with their slots in juxtaposed relationship, the ends of the pin 16 are in said slots: it being understood that the length of the pin 16 is slightly less than the combined width of both guide plates. It

is to be noted that, whereas the overall thickness of the plate 33 is much greater than that of the plate 32, the former plate is relieved a sufficient amount throughout certain portions of its width to provide an accommodating passageway for the upper portion of the frame member 12 and the base of the finger 22. This relieved area enables the head portions of the device to be assembled with the upright frame member 12 sandwiched between the two guide plates 32, 33; and the guide slots 34, 35, cooperating with the stationary pin 16, permit limited manual shifting movement of the movable head portion in a vertical plane. The upper, or latch operating, end of the finger 22 protrudes from the upright frame member 12; and, when the movable head portion of the device is in the downwardly inclined position of Fig. 1, the upper end of this finger is nested in a longitudinal open slot or mortise 36 extending through a last mounting spindle 38. This spindle has an enlarged rectangular base portion 40 fitting into a receptacle therefor formed by adjacent cut-out openings 41, 42, respectively, through the upper portion of the two guide plates 32, 33. The spindle base is retained in fixed position within said receptacle, and therefore rigid with respect to the movable head plates 30, 31, 32 and 33, by a retaining screw 44 passing through the plates and through an opening in the spindle base.

Now, referring to Fig. 2, it will be seen that as the movable head portion 1 is lifted or shifted in a counterclockwise direction, thereby bringing the spindle to a more upright position, the free end of the stationary 30 finger 22 is left protruding outward from the side of the spindle; and, when this lifting movement is accomplished with a locked last L positioned over the spindle 38, the resultant relative movement of the spindle and last with respect to the free end of the finger 22 causes the latter to be engaged by the resilient free end portion E of the last link and the latching shoulder S to be deflected out of locking engagement (Fig. 1) with the latching pin P, whereupon continued upward force applied upon the forepart of the last will cause the last to be collapsed as illustrated in Fig. 2.

Referring again to Fig. 3, it will be noted that the thickened forward wall of the opening 42, in the guide plate 33, is provided with a small boss 46 projecting rearwardly into the cut-out opening 42 at a location adjacent the inside root of the curve 48, of the stationary finger 22; it being understood that, when the various parts are assembled, the boss 46 will extend slightly into the mortise 36 and, by contacting the root of the curved portion of the finger 22, it will thus establish a point about which the movable head portion of the device is free to oscillate relatively to the pin 16 along the arcuate path defined by the guide slots 34 and 35. The oscillatory movement of the guide plates 32, 33 in a clockwise direction is limited, or terminated, by the pin 16 engaging with corresponding ends of the moving slots 34 and 35, as shown in Fig. 1. However, the extent of movement in the opposite direction is limited by a stop pin 50 which abuts against a portion of the upright frame 12 before the pin can engage the opposite ends of the guide slots. This latter limiting action is designed to prevent the pin 16, during the operation of the device, from being in alignment with two juxtaposed openings 51, 53 through the outside plates 30, 31, because this pin, when in such an alignment, may readily be removed from the head assemblage, which is necessary in order to disassemble the device.

It may be seen from Fig. 2 that as long as the free end of the finger 22 projects as therein illustrated, the last will remain collapsed for the convenient mounting or removal of a shoe, regardless of how much downward pressure may be applied upon the forepart of the last. Therefore, in order to maintain the device in the condition shown in Fig. 2, a releasable latch 54 is provided on a pivoted lever arm 56 which is spring biased in a direc-

tion to cause the latch 54 to operatively engage with a notch 58 cut in the curved lower edge of the guide plate 32 (Fig. 3) when the head assemblage has been oscillated a sufficient amount to collapse the last. This notch 5 is located in such a position and is so designed that, when engaged with the latch 54, the movable head portion is thereby restrained against clockwise movement which might permit the closing and locking of the last, but it is not thereby restrained against a slight counterclockwise movement beyond the position of Fig. 2. The notch is purposely designed to allow movement of the head until the stop pin 50 strikes the frame plate 12. The reason for providing for this additional counterclockwise movement, when desired, is to allow the finger 22 to project slightly further into certain shoe lasts in which the free end E of the link might be positioned slightly more distant from the spindle socket than that position shown in the illustrated last. Such a variation in location may be encountered in lasts for shoes having very high heels and therefore steep shank portions which require a different positioning of the last link and pins with respect to the spindle socket in the last. When it is desired to lower the head assemblage to allow the last to be closed and locked, the latch 54 may be withdrawn from the notch 58 by manually depressing a handle 60 on the end of the lever 56, or, if desired, the device may be provided with a suitable foot-operated treadle mechanism, designated generally by the arrow 62, in Fig. 2, connected by a rod 64 to the lever arm 56.

In addition to the just described latching mechanism for holding the spindle in its upright position, the device is provided with a frictional ball detent which, when the device is in its normal inclined position of Fig. 1, automatically operates to steady the device in said inclined position so that a last readily may be placed on, or removed from, the spindle 38 without the operator holding the device to prevent such relative movement between the spindle and finger, as might cause the finger to protrude from the spindle and thus interfere with said placing or removing operation. Referring to Figs. 3 and 6, this detent mechanism comprises a V-shaped recess 66 cut into the wall of the frame member 12 adjacent the movable guide plate 33. Also, a cylindrical hole 68 is cut through the plates 31 and 33. This hole is so located that when the plates 31, 33 are in their inclined position of Fig. 1 the hole will be in axial alignment with the recess 66. The end of the hole 68 adjacent the recess has a reduced diameter forming a spherically tapered pocket or seat for a ball 70 which ball projects slightly beyond the seat formed in the plate 33. This ball is yieldingly pressed outward against the seat by a compression spring 72 nested between the ball and a retaining cup 74 threaded into the wall of the hole 68 in the plate 31. From the foregoing it will be perceived that when the device is moved to the position of Fig. 1, the projecting portion of the ball 70 will snap into the recess 66, and that when once so seated the force of the spring 72 will tend to hold the ball in the recess, thereby frictionally locking together the frame and head portion of the device while a last is being placed or removed. Of course, it is to be understood that the force of the spring 72 is insufficient to prevent the head from being forced in a counterclockwise direction, when it is desired so to do, thereby causing the ball to be temporarily cammed inward against the spring to permit relative movement between the head and frame portions. Referring to Figs. 3, 4 and 5, it will be noted that a cam surface 76 is formed by removing a portion of the vertical front corner of the frame plate 12 on the side adjacent the guide plate 33. The inclined surface thus formed serves as a cam to force the ball 70 back into the hole 68 when the device is approaching the inclined position of Fig. 1, and to thus allow the ball seat to be placed readily in alignment with the recess 66, at which location the ball 70 will interlock the plates 12 and 33.

Having thus described my invention, what I claim as

new and desire to secure by Letters Patent of the United States is:

A last operating device for opening shoe lasts, comprising: a frame member; an inclined stationary finger protruding in a vertical plane beyond said member and adapted, when caused to extend through a vertical opening in a last spindle socket, to operatively engage with a latching arm of a last link; a movable last mounting spindle provided with a longitudinal mortise to receive said finger and enclose it therein when the spindle is in an inclined last receiving position; spindle-carrying guide means movably connected to the frame member and finger so as to limit the motion of the spindle to a pivotal swinging movement along the vertical plane of the finger, whereby the spindle may be pivotally moved away from its inclined last receiving position to a more vertical posi-

tion thus exposing the finger and bringing the latching arm into operative engagement with the finger; and a manually releasable detent engageable with the spindle-carrying guide means to positively hold the spindle in said vertical position.
